UNITED STATES PATENT OFFICE.

HENRY M. WILLIS, OF EAST WILLISTON, NEW YORK.

ROAD-CART.

SPECIFICATION forming part of Letters Patent No. 447,391, dated March 3, 1891.

Application filed June 16, 1890. Serial No. 355,547. (No model.)

To all whom it may concern:

Be it known that I, HENRY M. WILLIS, of East Williston, in the county of Queens and State of New York, have invented a certain new and useful Improvement in Carts, of which the following is a specification.

The improvement is intended for that class of two-wheeled vehicles known as "carts" used for racing, pleasure riding, and business purposes, equipped with liberally-yielding springs, and adapted for fast driving over either smooth or rough roads. Each side of the body is provided with a stout horizontal top bar or rave, which forms a substantial attachment for the springs and thills. I connect the thills to the top bars by means of springs rigidly held both to the body and thills, so that the connection is elastic as distinguished from pivotal, and such connection is made in rear of the front of the body, so as to reduce the amount of flexure of the springs with a given degree of tilting of the body. I have no pivotal connection. I employ a safety-stop on each side in the form of a rigid arm extending from the thill inward to a point under the rave or top bar, and I inclose each arm in a slot in an iron bolted to the rave, which allows it to play up and down as far as is ever required in the use of the cart while in motion, but arrests it strongly and reliably whenever any too much motion is impressed, as when a heavy man steps on the rear edge of the body in mounting or stands in the front of the body after mounting; and I combine with this still another safety-stop near each side at the front in the form of a safety-strap connecting the front of the body to the whiffletree-bar adjusted so as to provide slack for the proper motion. So long as the cart is only slightly shaken, as by the "horse motion" in being drawn by a horse at a trot, the spring-connections of the thills to the body are alone effective; but when from any cause the body is very greatly tilted relatively to the thills both the pairs of stops become effective to restrain the motion and prevent the distortion from breaking the springs, the safety-straps being drawn downward or upward until the slack is taken up, and then firmly holding the body against further movement in that direction, and the arms and slots also performing a similar duty, allowing

the body to tilt its front downward or upward freely until the arms have reached the bottoms or tops of the corresponding slots. These two sets of stops thus form a double provision to insure the safety of the cart against a too great pitching motion. Further and more important, these two sets of stops are ready to serve usefully in their relations to each other in the rare event of the fracture of the springs which connect the body to the thills. In such case the body is free to tilt somewhat farther than usual; but when it has tilted to a certain extreme extent it is restrained. The two sets of stops are effective to prevent it from tilting indefinitely. If the front tends to move downward, as is usually the case in practice under such circumstances, the hind ends of the thills are held up by the slots, and the front end of the body is held up by the safety-straps; or if the body tends to tilt the other way—backward—as might happen if the driver leaned backward on the seat, the front of the body will rise; but its rise will soon find a limit in the relations of the two sets of stops. The hind ends of the thills are held down by the engagement of the arms in the slots, the arms rising therein and striking the under face of the side bars, and the front end of the body is held down by the safety-straps. In what I esteem the most complete form of the invention I provide two sets of such arms, one well back near the hind end of each thill, ready to exert a long leverage with the safety-straps and to sustain the body when the springs break, if such a disaster shall ever occur, and the other set well forward, in position to serve well in performing the more usual duty of restraining the tilting of the body relatively to the thills under ordinary conditions when no fracture has occurred.

It is sometimes required to connect the body and thills unyieldingly. This is especially necessary in racing, as the irregular motion due to an elastic connection tends to throw the horse off his gait. I apply a removable bar across the top of the front and hold it rigidly upon the top of both the raves and the thills, providing means for also holding these parts firmly up against the removable bar. This bar is applied and removed as required.

The following is a description of what I consider the best means of carrying out the invention.

The accompanying drawings form a part 5 of this specification.

Figure 1 is a side elevation, and Fig. 2 is a plan view, of my cart complete. Figs. 3 to 8, inclusive, are on a larger scale, and show parts of the same. Fig. 3 is a side elevation. 10 Fig. 4 is a plan view. Fig. 5 is a front view. Fig. 6 is a front view of another part. Fig. 7 is a cross-section on the line $y-y$ in Figs. 3 and 4; and Fig. 8 is a cross-section on the line $x-x$ in the same figures. Fig. 9 is a partial 15 plan view showing the front portion of the body set free by the removal of the removable bar. This figure shows also a modification in the form of the spring connection of the thills to the body. It also shows a less 20 number of sets of stops.

Similar letters of reference indicate like parts in all the figures where they appear.

A is the body, and A' the top rails extending forward and backward on each side, 25 sometimes known as "raves." A² is a corresponding top piece extending across the front of the body.

D is the spring, rigidly secured by clips to the axle L and to the top rail or rave A' on 30 each side. It performs the function of providing for the up-and-down motion of the body and axle relatively to each other.

M M are the thills, connected, as usual, by a whiffletree-bar M', which latter extends 35 across just in front of the front rave or front top rail A², but at a sufficient distance to allow all usual irregularities of motion without touching. P P are safety-straps connecting these parts A² and M' loosely together near 40 each side by taking hold of irons under each, as shown in Figs. 5 and 6.

D D are flat springs of tempered steel bolted rigidly to the under sides of the raves or top rails A' by bolts d at about mid-length 45 of the body, and held rigidly to the under sides of the rear ends of the thills M by the clips m. The springs are U-shaped in plan, being each upset or otherwise thickened in the curve, so that but little of the flexure is 50 concentrated there. The straight portions, extending front and rear, are well conditioned to hold the body to the thills without looseness and without any pivotal action, but with liberal elasticity. A short plate N, of 55 iron, is held firmly on the under side of the spring, and the rear end of this iron and also of the thill M is rounded, as shown at M* N*, to attain what is sometimes termed a "cushioning action"—a change of the terminal 60 point of bearing as the spring is bent in one direction and the other.

O O are arms extending inward toward the body from each thill M alongside the body. These arms are rigidly held on the thills by 65 clips m, and are provided at their inner extreme ends with hooks or right-angled parts O' O', and are inclosed in slots in sufficiently-

stout irons bolted under the top rails. These irons are marked a and are held by bolts a'. The arms O reach through slots in their respective irons a, and the hook O' on each stands properly conditioned to be struck by the iron in case of too great lateral vibration. 70

U U are arms similar to the arms O O, and provided with corresponding hooks U' U', 75 similar to the hooks O' O'. These hooks and arms are similarly engaged with slotted irons a², held to the top rails A', forward of the irons a, by bolts a².

W is a removable bar lying across the cart 80 near the front of the body A and provided with two bolts X X, each having a cross-bar X' X' at its lower end and a thumb-nut X² X² at its upper end, the latter being threaded to allow of conveniently tightening and slackening. For a race the bar W is put in position with the cross-bars X' X' turned to allow of their being depressed with their respective bolts X X through the space between A' and M, and then the cross-bars X' X' are 85 turned into the proper crosswise positions and the thumb-nuts X² X² are set tightly. This holds the front of the body A rigidly to the thills, and the only motion relative to each other is the rising and sinking of the 90 back part of the body due to the action of the connecting-springs D in traveling over irregularities in the road or accommodating movements of the rider. Practically the body is rigid to the thills when thus conditioned. 95 When it is desired to set the body free, the thumb-nuts X² X² are slackened, the cross-bars X' X' turned again fore and aft, or in lines from front to rear, and the bar W is then 100 lifted, with its attachments, and removed. 105

In the use of the cart with the bar W in place, the front of the body, and in effect the whole body, is stiffly attached to the thills. In the ordinary use of the cart with the bar W removed the body is free to tilt forward 110 and backward, except as it is held by the easy springs D, until it has tilted a certain distance. Then its further tilting relatively to the thills is arrested by the three sets of stops—first, the safety-straps P, the slack of 115 which is limited and has then been taken up; second, the arms O O, loosely confined in the slotted irons a, which have now reached their extreme downward or upward limit, and, third, the arms U U, loosely confined in the slotted irons a², which have now similarly reached 120 their extreme limit. This latter set of stops—the arms U U in the irons a² a²—act more efficiently than the arms O O in the irons a a, because they are farther from the center of motion—the rear end of the corresponding spring D—and consequently have more leverage, or, as some would put it, a "greater movement of resistance."

In case of breakage of the springs D, which 130 is always possible, notwithstanding the limit to the deflection offered by the several sets of stops, new functions are developed in the stops. They serve to hold the body not only

to the thills, but in the approximately correct position. The stops co-act to prevent the body from tilting. The front stops are the safety-straps P. The rear stops are the arms O O. Each allows a little but only a little play. It follows that when the springs D D break, the body A remains horizontally supported. If it inclines to pitch forward, the straps P hold up and the arms O down 5 the parts adjacent, and if it inclines to pitch backward, the straps P hold down and the arms O hold up the same parts. The cart will be held fairly level, but subject, of course, to an objectionable irregularity of motion, until the springs can be repaired or replaced. 10

The hooks O' and U' are important. The safety-straps P can exert a very efficient influence to control the up-and-down motion; but they cannot serve well to resist side motions. 15 The hooks O' and U' are at such a distance from their respective irons a and a² that they are of no effect while the cart is unrestrained; but when in any exigency the body is violently twisted to one side, these 20 hooks arrest the motion and prevent its becoming excessive. 25

I attach importance to the fact that the thills are extended backward and connected elastically to the body at a point considerably in rear of the front, because the arrangement gives unusual freedom for the movement of the body within the limits prescribed, and allows the use of strong and substantial springs. The elastic attachment 30 of the springs is best made at about the mid-length of the body, as shown. 35

Modifications may be made by any good mechanic without departing from the principle or sacrificing the advantages of the invention. Parts can be used with advantage without the whole. I can dispense with one 40 of the sets of stops—as, for example, the arms U U—and the corresponding slotted irons a² a². In such case the single set of stops formed 45 by the arms O O, acting in the slotted irons a a, will serve, first, with the springs D D to limit the action thereof and prevent their being too much flexed, and afterward, in case of fracture of those springs, or of one of them, 50 the single set of stops O O will serve with the safety-straps P P to carry the body level, or nearly so, until the journey is ended; but both sets of arms O O and U U used together 55 make a better combination, because it is important to give as long a leverage as practicable between the bearings under each

condition, and when the effective bearings are the rear parts of the springs D D and the arms U U the bearings are well separated and the leverage is long, and when, after the 60 springs have broken, the effective bearings are the arms O O and the safety-straps P P the bearings are still well separated and the leverage in the extraordinary condition is also long. It is not possible to attain the 65 same effect under both conditions by a single set of arms O O and their loosely-inclosing irons a without the set of arms U U and their irons a².

I claim as my invention—

1. In a road-cart, the combination, with the body, supporting-springs, and axle, of additional springs affixed to the body at or near its mid-length, and the thills extending along the sides of the body independent and free 70 thereof and of the axle, and connected rigidly to the opposite ends of said additional springs, all arranged substantially in the manner and for the purpose specified. 75

2. In a road-cart having thills fixed to the body by elastic connections, a removable bar adapted to lie across the top near the front and bear fairly on both body and thills, in combination with such cart and with fastenings adapted to hold the body and thills 80 firmly to such bar when required and to conveniently and entirely release the parts when required for general use, as herein specified. 85

3. In a road-cart, the arms O O', extending between the thills and the body and rigidly 90 attached to one part, in combination with the irons a, slotted, as shown, and attached to the other part, and with spring connections D between the body and the thills, the hooks O' on said arms standing in position to defend 95 against too great lateral motion, as herein specified.

4. In a road-cart, the arms O O', affixed to the thills by means of the same clips which hold the thill and spring together, said arms 100 extending laterally and engaged with slotted irons on the body, adapted to allow a limited freedom of the motion, all substantially as herein specified.

In testimony whereof I have hereunto set 105 my hand, at New York city, this 13th day of June, 1890, in the presence of two subscribing witnesses.

HENRY M. WILLIS.
